J. T. GATTEN.

RAIL FASTENER.

APPLICATION FILED MAR. 18, 1919.

1,315,111.

Patented Sept. 2, 1919.

UNITED STATES PATENT OFFICE.

JOSEPH T. GATTEN, OF DANBURY, WISCONSIN.

RAIL-FASTENER.

1,315,111.

Specification of Letters Patent.

Patented Sept. 2, 1919.

Application filed March 18, 1919. Serial No. 283,396.

To all whom it may concern:

Be it known that I, JOSEPH T. GATTEN, a citizen of the United States, residing at Danbury, in the county of Burnett and State 5 of Wisconsin, have invented certain new and useful Improvements in Rail-Fasteners, of which the following is a specification.

This invention relates to an improved rail fastener and the principal object of the invention is to provide a fastener through the medium of which a rail may be securely held in engagement with a tie and prevented from having a tendency to work loose, the fastener being so constructed that it may be 15 tightened in case the tie should rot or wear at the point where the fastener is secured about the tie.

Another object of the invention is to so construct this fastener that it may be used 20 in connection with ties having a varying size as will be the case when ties are used which are formed of wood.

Another object of the invention is to so construct this tie that the rails will be prevented not only from having movement laterally of the tie but will also be prevented 25 from spreading.

Another object is to so construct this fastener that when it is desired to renew the 30 ties or rails, the rails may be easily released and either new rails or new ties put in place and the fasteners used again.

This invention is illustrated in the accompanying drawings, wherein—

35 Figure 1 is a top plan view showing a rail connected with a tie by means of the improved fastener,

Fig. 2 is a bottom plan view showing the fastener in place,

40 Fig. 3 is a perspective view of a tie plate or rail chair forming one of the elements of this fastener,

Fig. 4 is a perspective view of one end of a tie with which the fastener will be used,

45 Fig. 5 is a fragmentary sectional view showing a modified construction,

Fig. 6 is a perspective view of the clamp element shown in section in Fig. 5.

This fastener will be used for connecting 50 a rail 1 with the tie 2 and includes a tie-plate or rail shaft 3 which rests upon the tie 2 and is cut out to provide a seat 4 in which the rail will be seated. This rail seat or tie plate extends transversely of the tie and beyond the sides thereof as shown in Figs. 1 and 2 and will be provided with extensions

or arms 5 extending longitudinally of the tie. Openings 6 are formed in the tie plate upon opposite sides of the seat 4 and are arranged as shown so that the fastener may 60 be put in place as shown in Figs. 1 and 2 or may be extended in a diagonally opposite direction.

In order to secure the rail in place and hold the tie plate upon the tie there has been 65 provided fastening means consisting of eye-bolts 7 and a connecting rod or bolt 8 which extends through the eyes of the eye-bolts and in threaded engagement with one of the eye-bolts and will be positioned in a groove or 70 seat 9 formed in the tie. This seat or groove 9 will be cut in the tie according to the direction in which it is desired to have the rod or bolt 8 extend and therefore it will be seen that this rod may extend either as shown in

Fig. 2 or in the opposite direction. It will be further seen that when in place the rod will be prevented from moving longitudinally of the tie and the plate 3 thus held 75 against movement in this direction. The eye-bolts 7 extend through the openings 6 and carry securing nuts 10 which engage the sloping upper faces of the rail face and when tightened will securely clamp the rail in the seat 4 thus holding the rail against 80 vibration. Tightening of the securing nuts 10 will further serve to securely clamp the plate 3 upon the tie. After the nuts 10 have been tightened the desired amount the set-screws 11 will be tightened and will engage 85

the bolts thus securely locking the nuts 10 and preventing them from working loose. It is to be understood that the nuts 10 may be locked upon the bolts 7 in any desired manner. In the modified construction dis-

closed in Figs. 5 and 6 there has been shown 90 a structure which may be used in place of the eye-bolts 7. In this form there is pro-

vided a clamp including a body portion 12 having an eye 13 through which the rod or bolt 8 is passed. This clamp will extend 95 along the side of the tie and will be provided with a cut-out forming a pocket 14 terminat-

ing in a passage 15 through which a small bolt 16 will pass, the head of the bolt 16 100 being positioned in the pocket 14. This bolt 16 will extend through the plate 3 and a

securing nut 17 corresponding to the nut 10 is threaded thereon. It is of course under-

stood that the pocket 14 of the clamp portion 110 12 will be of sufficient length to permit inser-
tion of the bolt 16. When this form is used

the tie plate is secured with two such fasteners extending across the tie at right angles instead of diagonally. When the securing bolts 8 of these several fasteners are 5 tightened the clamping arm 12 will tightly grip the sides of the tie and the plates will be securely held upon the tie.

When this device is in use the ties will be put in place upon the roadbed and the 10 rails extended to rest upon the end portions of the ties with the tie-plates or rail chairs upon the ties beneath the rails and the rails resting in the seats 4. The clamps will be put in place in the form shown in Figs. 1 15 and 2, the eye-bolts 7 will be passed through the opening 6 with the rod 8 fitting in the seat 9 and the securing nuts for the bolts 7 and rod 8 then tightened. If the form shown in Figs. 5 and 6 is used the bolts 16 20 will be passed through the openings 6 and the securing nuts of these bolts tightened, the securing nut for the bolt 8 being also tightened thus securely clamping the bars or clamps 12 to the tie and securely holding 25 the plate 3 in place. When a rail has been secured by this improved fastener it will be securely held in place against movement thus preventing danger of a spreading rail. At the same time the rail may be easily 30 released when necessary by simply releasing the fastening means for the plate 3. I have therefore provided a rail fastener so constructed that the rails may be securely held in place and have further so constructed this fastener that they may be easily and quickly released when desired and the fastener used over again.

What is claimed is:

1. In a structure of the character described, a rail supporting plate, a connecting rod, clamping arms fitting loosely upon the connecting rod and having their free ends provided with cut-outs forming pockets terminating in reduced openings, and securing bolts passing through the pockets 45 and openings and engaging the plate.

2. A rail fastener comprising a tie-plate, means for holding the plate upon a tie comprising tie engaging clamping arms positioned beneath the plate for engaging opposite sides of a tie, adjustable means connecting the arms to retain the arms in tight engagement with a tie, and securing means connecting the clamps with said plate and extending to engage a rail and hold the rail 55 upon the plate.

3. A rail fastener comprising a tie-plate, and securing means carried by said plate and including clamping arms for engaging a tie and means for connecting the clamping arms with the plate, the last mentioned means constituting means for holding a rail upon the plate.

4. A rail fastener comprising a tie-plate, and securing means for the plate including 65 tie engaging elements, means adjustably connecting the engaging elements and common means holding the tie engaging elements in engagement with the plate and engaging a rail to hold the rail seated upon 70 the plate.

In testimony whereof, I affix my signature hereto.

JOSEPH T. GATTEN.
